WARP TWISTING-IN MACHINE

John H. Becker, Ridgewood, N. J., assignor to
Warp Twisting-In Machine Company, New
York, N. Y., a corporation of New York

Application July 23, 1936, Serial No. 92,132

10 Claims.

(Cl. 28—48)

In Patent No. 1,403,067 and those therein mentioned there is disclosed a machine known as a warp twisting-in machine for uniting the threads of the old warp, wound on the take-up beam and extending through the harness of a loom, with those of a new warp, wound on a beam to replace in the loom the let-off beam for the old warp. In the twisting of each new warp thread with the complementary old warp thread the ends 5 of the two threads are twisted together to form a twisted tail and then this twisted tail is twisted around the new warp thread, thus producing a composite twist or union which will pass through the corresponding heddle of the harness. The machine comprises the following 10 mechanism, generally stated: Means, as a clamp, to initially hold the free ends of both warps as they extend in opposite directions from their beams; means to segregate from the respective warps the threads to be twisted together, such 15 means maintaining leases in the warps; means to advance such threads from the warps to the position for undergoing twisting; and means for effecting the twisting comprising members, one 20 rotary relatively to the other, which clamp the threads and hold them, in coaction with the beams and during the twisting, in the initial state of tension effected by the coaction of the mentioned clamp with the beams, it being understood 25 that after such clamping is effected by said members the threads are severed between them and the clamp.

Threads which have considerable resistance to twisting and are quite wiry, for instance, hard-sized threads of synthetic yarn, do not readily respond to the twisting action as the machine was heretofore constructed; sometimes a union of the threads did not occur at all, and frequently the union formed is so weak and the twist is so lacking in compactness that when the resulting composite strand is drawn through its heddle of the harness it parts at the twist or such twist becomes caught on the heddle. According to this invention, as considerable practice has shown, 30 this fault has been completely overcome.

Again, when the threads are advanced to the position for the twisting they have been held heretofore in a fixed holding fork or thread holder, wherefore at the outset of the twisting operation the effort to twist was sometimes abortive and involved an undue strain on the threads. My invention also contemplates providing for 35 movement of this fork or thread-holder which shall be compensatory with reference to the initial 40 rolling, with twisting, of the threads. This im-

provement is not indispensable, but it reduces the chance of failure to start the rolling with twisting.

In the drawings,

Figs. 1 and 2 are, respectively, a front and a 5 left side elevation of the improved machine, Fig. 2 showing diagrammatically the harness, take-up beam and new warp beam;

Figs. 3 and 4 are, respectively, a front elevation and a plan, both on a larger scale, of that part of 10 the machine directly involving the invention;

Figs. 5 and 6 are right and left side elevations, respectively, of what is shown in Figs. 3 and 4;

Figs. 7 and 8 are sections on lines 7—7 and 15 8—8, respectively, of Fig. 6;

Figs. 9 to 16 show the twisting pads as seen in 20 Figs. 7 and 8 and the associated parts in the positions they occupy successively from the inception to the completion of the twisting and delivery of the threads as a composite or single strand; 25 and

Fig. 17 is a plan of a modification, showing the 30 holding fork or thread-holder movable.

In the frame 1 vertically reciprocates a structure 2 having the mentioned clamp 3 for the old 25 warp *b* and new warp *a* and also, at its lower portion, the forwardly projecting rods or presser feet 4 to bear on the warps (when said structure descends) between the rods 5 of the frame over 30 which the warps extend. *b'* and *a'* are the harness and beam. The clamp initially coacts with the take-up beam *b2* in the loom and with beam *a'* to hold the two warps in tension. Leases are maintained in the two warps and two threads at 35 a time (one from each) are segregated from the warps by the hook-bar pairs 6 which are rotated half-revolutions at a time and on each such movement retract. The segregated threads are advanced by the rotary spiral 7 lengthwise of a fork 8 which slides forward and back in the 40 frame, these threads finally coming into engagement with its slender upturned hook-like ends 8a (i. e., in position for the twisting of such threads together), entering a stationary holding fork or thread-holder 9. A fixed shaft 10 carries 45 the support 11a for the stationary twisting pad 11 and a rotary shaft 12 carries the support 13a for the rotary twisting pad 13; the pads may be associated with their supports as shown in my Patent No. 1,706,390, so as to be elastically urged 50 toward each other when they are in action, or effecting twisting; the pads form members to clamp the threads, as will appear. Means, not shown but clear from the patents first mentioned herein, drives the structure 2, the hook-bars, the 55

fork, the spiral and the shaft 12 for the rotary pad 13 so that said structure and fork 8 each reciprocate and the spiral and shaft 12 perform a full revolution and the hook-bars a half-revolution all in properly timed relation to each other and as explained in the mentioned patents. The warp *b* extends from one rod or presser foot 4 and under the shaft 12 and then to fork 8, and warp *a* extends from the adjoining rod or presser foot 4 directly to said fork as shown in Fig. 2. When the two threads *a** and *b** engaged with the ends 8a of fork 8 have been brought forward to position (having cleared rods 4) for twisting together by the pads (Figs. 5, 6 and 9 to 11) and the pad 13 has rotated sufficiently to clamp both threads the upstanding portions of the threads are severed (Fig. 11) by the device 14 which is fulcrumed on the support 11a for the stationary pad and obtains its severing movement from a cam 15 on shaft 12, and then said fork retracts to permit continued rotation of pad-support 13a, all also as substantially disclosed by said patents.

Insofar as the pad 13 is shown tapering and in the example with a planiform acting face and the pad 11 has a recess *x* in its acting face separating two ribs *y* and *z*, with a notch *x*2 at the lower end of rib *y* and a table *x*3 below the recess, it follows a known construction, the operation of which as the pads are thus constructed (cf. Landefear's Patent No. 1,424,276 and my Patent No. 911,885, and see the Goss Patent No. 648,738) it is pertinent to describe in order to have a proper understanding of my present invention: Thus, the two threads being held by the ends 8a of fork 8 (initially) and in the thread-holder 9 in the plane of the acting faces of the pads (Fig. 9), they are clamped by the pads and so started rolling (Fig. 10) and are then severed (Fig. 11), such rolling being effected as to the outer ends of the illustrated bent-off terminals of their clamped free end portions by pad 13 and rib *y* and resulting in the forming of a tail *c* (Fig. 12) while said terminals are clamped, with less rolling speed, by pad 13 and rib *z* (fork-ends 8a having by this time retracted clear of the threads). As the tail rolls around, it and thread *a** come into the notch *x*2 whereby the rolling, theretofore effected between pad 13 and rib *y*, ceases while the rolling of the inner end of the tail with thread *a** continues to be effected by pad 13 and rib *z*, this developing a composite twist of the twisted tail with thread *a**, such composite twist finally rolling out of notch *x*2 so that it is next rolled bodily between pad 13 and table *x*3 and the united threads delivered as a composite strand. It is essential to this operation that the terminal of at least the thread *a** be initially bent off, as in Fig. 9.

The twisting mechanism as it thus is formed and operates has proven in extensive use through many years altogether satisfactory where the threads manipulated did not have the superior resistance to twisting and wiry nature of hard-sized yarns. But when it is attempted to form a stable and properly compact composite twist in threads having such superior resistance and wiry nature it is found that the reverse or outward twisting as between the twisted tail and thread *a** (which is supposed to ensue due to such tail and thread being in notch *x*2 while pad 13 and rib *z* continue their rolling action at the inner end of the tail) fails to do so, or at least occurs so incompletely that the union is weak or is not compactly formed, or both, so that an imperfect composite strand results, and in any event the

mechanism does not reliably perform its intended operation on threads of such character.

I have found that if thread *a** is held against advance until and after tail *c*, having been twisted and so formed, coincides with it, this fault may be overcome and that threads having the superior resistance and wiry nature indicated can with reliability and with sufficient tightness be twisted together to form a strong and properly compact composite twist. This I accomplish in this example by a detent 18 to be described. Preferably to discourage any tendency of thread *a** to be rolled notwithstanding, and incidentally to be strained because of, the detent until tail *c* coincides with it I form in rib *y* above notch *x*2 another notch *x*'. When the tail *c* has been rolled into this notch *x*' the rolling of the inner end of the tail around thread *a** begins, thus to develop (in the outward direction) the composite twist *c*' (Fig. 13); thereafter the detent device 18 may begin to fall or retract more or less at the same rate as the progress, incident to rolling, of the inner end of the tail around thread *a** proceeds. Finally, if notch *x*2 is retained, as shown, the composite twist becomes so far developed in this way that it rolls out of the notch *x*' (Fig. 14) and comes to a pause again in notch *x*2, being then subjected to a further twisting effort as its inner end is rolled between pad 13 and table *x*3 while its outer end occupies this notch, detent 18 meanwhile still retracting (see Fig. 15). Fig. 16 shows the composite strand *d* delivered, for which purpose the detent has retracted clear of thread *a** (see the detent as shown dotted in Fig. 5).

The detent 18 is fulcrumed in a bracket 17 attached to support 11a at the new-yarn side thereof, being a lever which moves in a nearly vertical fore-and-aft plane from the full line position of Fig. 5, where it is shown extending through the plane of the coating faces of the pads, to the dotted position. Connected with it is an actuating lever 19 (Fig. 3) fulcrumed on said support to move in a vertical transverse plane and having a notch 19a in one end receiving a projection of the lever and its other end held bearing against a cam 15a (forming part of cam 15) by a plate-spring 20 affixed to said support. Notch *x*' is so positioned as to coincide with thread *a** at the outset (Fig. 9), and when pad 13 is about to approach the threads the cam 15a brings the detent to thread-supporting position. The detent having served to support said thread until the twisting shown in Fig. 13 is at least well under way, the cam then permits it gradually to retract in response to spring 20, until finally the detent clears the plane of twisting altogether (Fig. 5, dotted) to permit delivery of the composite strand *d*.

When the thread-holder is fixed, as previously assumed, the threads are not only subject to strain augmenting that of the tension imposed on them at the outset when they are secured in the clamp 3 (such strain being incident to the initial effort to roll them around each other and so twist them together—see Fig. 10), but sometimes the effort to start the twist is abortive or at least unduly postponed. Hence, according to the construction of Fig. 17 I mount the thread-holder, 21, on the support 11a so as to be movable in the general direction in which the threads shift in response to action of the rotary pad. It is here made to obtain such movement through transmission means afforded by the cutter device 14 and a link 22 connecting them. When the

threads begin to be clamped by the pads, and hence their rolling action starts, and until said device severs them, the thread-holder moves compensatingly, or generally in the same direction as the threads shift, wherefore the thread-holder does not interfere with the tendency of the threads to roll and they are not unduly strained.

Having thus fully described my invention what I claim is:

1. The combination, with means from which respectively extend threads one of which is to be united with the other and twisting mechanism including, with supporting means, members between which the free end portions of the threads are clamped with the terminals of such portions extending generally in the same direction and close together and the terminal of said portion of the first named thread bent off, one member being movable relatively and in thread-clamping relation to the other first to twist said terminals together to form thereof a twisted tail and then to twist such tail around the remaining portion of said first-named thread which lies between said members to form a composite twist, of means on the supporting means to oppose displacement, during the twisting, of the part of the first-named thread which is between the means from which such thread extends and said members.

2. The combination, with means from which respectively extend threads one of which is to be united with the other and twisting mechanism including, with supporting means, members between which the free end portions of the threads are clamped with the terminals of such portions extending generally in the same direction and close together and the terminal of said portion of the first-named thread bent off, one member being movable relatively and in thread-clamping relation to the other first to twist said terminals together to form thereof a twisted tail and then to twist such tail around the remaining portion of said first-named thread which lies between said members to form a composite twist, of a detent movable on the supporting means to a position to oppose displacement of the part of the first-named thread which is between the means from which such thread extends and said members, and means to move said movable member and, during the twisting, move said detent to said position.

3. The combination, with means from which respectively extend threads one of which is to be united with the other and twisting mechanism including, with supporting means, members between which the free end portions of the threads are clamped with the terminals of such portions extending generally in the same direction and close together and the terminal of said portion of the first-named thread bent off, one member being movable relatively and in thread-clamping relation to the other first to twist said terminals together to form thereof a twisted tail and then to twist such tail around the remaining portion of said first-named thread which lies between said members to form a composite twist, of a detent movable on the supporting means to a position to oppose displacement of the part of the first-named thread which is between the means from which such thread extends and said members, and means to move said movable member and, during the twisting, move said detent to and then from said position.

4. The combination, with means from which respectively extend threads one of which is to be united with the other and twisting mechanism

including, with supporting means, members between which the free end portions of the threads are clamped with the terminals of such portions extending generally in the same direction and close together and the terminal of said portion of the first-named thread bent off, one member being movable relatively and in thread-clamping relation to the other first to twist said terminals together to form thereof a twisted tail and then to twist such tail around the remaining portion of said first-named thread which lies between said members to form a composite twist, of a detent movable on the supporting means to a position to oppose displacement of the part of the first-named thread which is between the means from which such thread extends and said members, and means to move said movable member and, during the twisting, move said detent to, and during the second-named part of the twisting, move said detent from, said position.

5. The combination, with means from which respectively extend threads one of which is to be united with the other and twisting mechanism including, with supporting means, members between which the free end portions of the threads are clamped with the terminals of such portions extending generally in the same direction and close together and the terminal of said portion of the first-named thread bent off, one member being movable relatively and in thread-clamping relation to the other first to twist said terminals together to form thereof a twisted tail and then to twist such tail around the remaining portion of said first-named thread which lies between said members to form a composite twist and the other member having, in its clamping face and adjacent the means from which the first-named thread extends, a notch to receive such thread, of means on the supporting means to oppose displacement, during the twisting, of the part of the first-named thread which is between the means from which such thread extends and said members.

6. The combination, with means to hold a pair of threads taut, of means to hold taut portions of the threads close together including a movable thread-holder, members between which said portions are clamped one of which is movable relatively and in thread-clamping relation to the other in the direction to coast therewith to twist said portions together, said thread-holder being movable in the general direction in which the threads shift when said portions are twisted together, and supporting means for said members and thread-holder.

7. The combination, with means to hold a pair of threads taut, of means to hold taut portions of the threads close together including a movable thread-holder, members between which said portions are clamped one of which is movable relatively and in thread-clamping relation to the other in the direction to coast therewith to twist said portions together, said thread-holder being movable in the general direction in which the threads shift when said portions are twisted together, means to transmit motion from said movable member to said thread-holder, and supporting means for said members, thread-holder and third-named means.

8. The combination, with means to hold a pair of threads taut, of means to hold taut portions of the threads close together including a movable thread-holder, members between which said portions are clamped one of which is movable relatively and in thread-clamping relation to the other

- in the direction to coact therewith to twist said portions together, said thread-holder being movable in the general direction in which the threads shift when said portions are twisted together,
5 means to transmit motion from said movable member to said thread-holder including a device to sever the threads, and supporting means for said members, thread-holder and third-named means.
10. 9. The combination, with means to hold a pair of threads taut, of a member against which the taut portions of the threads are adapted to bear, a movable system including a member movable relatively and in thread-clamping relation to the first member and coactive therewith to twist together the clamped portions of the threads and a thread-holder holding said clamped portions close together, said second-named member and
- 15 thread-holder being connected to move simultaneously and in generally the same direction, and supporting means for said system.
10. The combination, with means to hold a pair of threads taut, of a member against which the taut portions of the threads are adapted to bear, a movable system including a member movable relatively and in thread-clamping relation to the first member and coactive therewith to twist together the clamped portions of the threads, a 10 thread-holder holding said clamped portions close together, and a cutter-device to sever the threads, said second-named member and thread-holder being movable in generally the same direction and simultaneously with the cutter-device, and 15 supporting means for said system.

JOHN H. BECKER.
